United States Patent Office

Des. 232,754

Patented Sept. 10, 1974

232,754

CHARM OR SIMILAR ARTICLE

Bernard Bernstein, 3224 Bronx Blvd.,
Bronx, N.Y. 10467

Filed Feb. 2, 1973, Ser. No. 328,907

Term of patent 14 years

Int. Cl. D11—01

U.S. Cl. D45—17

The figure is a plan view of a charm or similar article, showing my new design.

The opposite surface is smooth and unornamented. The side edge is of conventional thickness and unornamented.

I claim:

The ornamental design for a charm or similar article, as shown and described.
